UNITED STATES PATENT OFFICE.

JOHN A. HULIT, OF CHICAGO, ILLINOIS.

TELEGRAPH SENDING INSTRUMENT.

Application filed June 12, 1922. Serial No. 567,541.

To all whom it may concern:

Be it known that I, JOHN A. HULIT, a citizen of the United States, and a resident of Chicago, Cook County, Illinois, have invented a certain new and useful Improvement in Telegraph Sending Instruments, of which the following is a specification.

This invention relates to telegraph sending instruments in general, and more particularly to those in which means are provided for sending a plurality of dots by only a single pressure of the lever or telegraph key, and is in the nature of an improvement on the construction disclosed in prior application No. 536,612 filed February 15, 1922 for a similar instrument.

Generally stated, therefore, the object of the invention, and of the improvement hereinafter described, is to provide an improved construction arrangement whereby only a single make and break device is included in the telegraph line circuit, in combination with a constantly operating friction drive connection for operating the instrument, and certain other desirable elements, as will hereinafter more fully appear.

It is also an object to provide certain details and features of construction and combinations tending to increase the general efficiency and desirability of a telegraph sending instrument of this particular character.

To these and other useful ends the invention consists in matters hereinafter set forth and claimed and shown in the accompanying drawings in which—

Figure 1 is a plan view of a telegraph sending instrument embodying the principles of the invention.

Figure 2 is a side elevation of said instrument.

Figure 3 is an end elevation of said instrument.

Figure 4 is a transverse section on line 4—4 in Figure 1.

Figure 5 is a transverse section on line 5—5 in Figure 1.

Figure 6 is a transverse section on line 6—6 in Figure 2.

Figure 7 is a detail view.

Figure 8 is a transverse vertical section on line 8—8 in Figure 7.

Figure 9 is a transverse section on line 9—9 in Figure 7.

As thus illustrated, the invention com-

prises a suitable base 1 upon which is mounted a more or less rectangular frame 2, and also an electric motor 3 of any suitable character. A longitudinally disposed drive shaft 4 is supported at one end in a bearing 5 on the frame, and has its other end suitably connected by worm gearing (not shown) in the housing 6, which gearing is driven by the motor to rotate the shaft 4 at the required speed. This shaft is provided with a pinion 7 to engage the gear wheel 8 on the shaft 9 which is supported by the frame 2 previously mentioned. Another gear wheel 10 is adjacent to the gear wheel 8, loosely on the shaft 9, and a friction connection 11 is provided between the two opposing flat surfaces of the gear wheels, whereby rotation of the gear wheel 8 will produce rotation of the gear wheel 10, under certain conditions. A spring 12 is arranged to press the gear wheel 10 toward the gear wheel 8, thus ensuring the desired or necessary degree of friction to produce rotation of the gear 10 when the latter is not held normally in a stationary position.

The make and break device to be operated by the gear 10, in sending messages, comprises a shaft 13 extending longitudinally of the frame 2 and provided near its rear end with a pinion 14 to engage the gear wheel 10, in the manner shown. Outside of the frame 2, shown more clearly in Figure 4, the shaft 13 is provided with a ratchet wheel 15, and a vibratory arm 16 is pivoted at 17 on the frame to swing about a horizontal axis, and to engage the ratchet wheel 15 at its upper end. The lower end of this arm 16 has a contact 18 to engage and disengage the stationary contact 19, which latter is adjustable by means of the screw threaded elements 20 to regulate the gap of this make and break device which controls the line circuit. A spring 21 is arranged to pull the arm 16 into position to close the make and break device, but the gap of this device is normally open, as shown, so that the line circuit is normally open. It will be understood that the two contacts 18 and 19 of the make and break device can be included in the line circuit in any suitable or desired manner. When the gear wheel 10 is rotated, the pinion 14 is thereby rotated and this rotates the shaft 13 and

causes the ratchet wheel 15, or any suitable toothed wheel, to rotate and operate the arm 16 about its axis to cause an opening and closing of the make and break device, 5 when it is desired to send a plurality or series of dots. However, when it is desired to send a dash, then the shaft 13 is allowed to rotate only just enough to release the arm 16 from its normal position, so that 10 the contact 18 will engage the contact 19, and this closure of contacts continues until the dash has been transmitted, and then the circuit is opened again.

The telegraph key or lever mechanism 15 which controls the rotation of the shaft 13, thereby to determine whether dots or dashes shall be transmitted, and in what manner, is as follows: The telegraph key or lever 22 by which the dots are transmitted is pivoted 20 at 23 to swing about a vertical axis, this pivot being formed by vertical member 24 supported in the frame in any suitable manner. This lever 22 carries adjustable screws 25 for engaging the spring 26 carried in the frame member 27, so that the lever is held outward against the stationary screw 28 which forms an adjustable stop for limiting the outward movement of the lever, this screw 28 being supported on the frame in 30 any suitable manner. An adjustable screw 29 is provided on the lever 22 for engaging the frame member 30 which forms a stop to limit the inward movement of said lever. The key lever 31 for sending the dashes is pivoted at 32, so that it swings about a vertical axis, this axis being provided by a member 33 supported in a suitable manner in the frame. This lever 31 has an adjustable screw 34 for engaging the coil spring 35 in 40 the member 27, so that the lever 31 is normally held outward against the stationary stop provided by the adjustable screw 36, which latter is also suitably mounted on the frame. An adjustable screw 37 is inserted 45 through the lever 31 to engage the stationary stop 30 previously mentioned, whereby the inward movement of this lever 31 is limited. With this construction, the two key levers can be regulated to ensure the proper operation or 50 action thereof. The shaft 13 has its front end provided with a ratchet wheel 38, and ratchet dogs 39 and 40 are suitably pivoted on the frame to engage and disengage said ratchet wheel, these dogs being controlled 55 by springs 41 and 42, respectively, which pull the upper ends of the dogs into engagement with the ratchet wheel. The pivots for the two dogs are at 43 and 44, so that they operate about longitudinally and horizontally disposed axes during the operation of 60 the instrument. The lever 22 has a projection 45 for engaging the lower end of the dog 29, to release the latter from the ratchet wheel 38, thereby to send a series of dots, as

the shaft 13 will rotate as soon as it is released by this dog, with the result previously described. In other words, a series of dots will be transmitted as long as the lever 22 is held in its actuated position, for at such time the dog 39 is disengaged from the ratchet wheel 38 and the make and break device previously described is free to operate until, in the judgment of the operator, the correct number of dots has been transmitted. The lever 31 has a hook 46 which engages a 75 pin 47 on the dog 40, so that this pin is normally held out of engagement with the ratchet wheel 38, and only engages said wheel when the lever 31 is pressed inward. When the lever 31 is pressed inward it will be seen that the transverse screw 48 carried by the lever 31 engages the pin 49 on the dog 39, thus releasing this dog from the ratchet wheel. Consequently, what happens at this time, of course, is that as the dog 39 disengages the ratchet wheel 38 the shaft 13 turns a little but stops as soon as the pin 47 of the dog 40 enters and engages the ratchet wheel, thus holding the make and break device closed to transmit a dash which will 90 continue as long as the lever 31 is held in operative position.

Thus it will be seen that a single make and break device 18 and 19 is operated by the constantly operating friction drive 8, 10 and 11, under control of two telegraph keys, to transmit either dots or dashes at will. The operator, if right-handed, will place the thumb on the key lever 22 and a finger on the lever 31, and will operate these levers laterally to transmit the dots and dashes in the manner required by the messages to be transmitted. With only a single make and break device, it becomes obvious that the spacing between a group of dots and a dash will be certain, and that all of such spaces will be uniform and of the same character. In other words, the dots are transmitted by the same make and break device by which the dashes are transmitted, and it follows that the transition from one to the other cannot take place too soon. For example, with some arrangements the transmission of the dash following a group of dots can take place too soon, or too close on the heels of the group of dots, and vice versa it is possible to start the transmission of a group of dots too soon and even before the transmission of the dash is fully completed, thus interfering with proper spacing. With the construction shown and described, however, comprising the single make and break device 18 and 19, which operates under control of the two key levers, it is impossible to start the transmission of a group of dots too soon after the transmission of a dash, and vice versa it is impossible to start the transmission of a dash too soon after the transmission of a group of dots.

sion of a group of dots, for there is only the one make and break device and the control thereover is such that the correct spacing is ensured.

5. With the construction shown and described, both the dots and the dashes are transmitted through the contacts 18 and 19, so that this single make and break point in the circuit is sufficient for both dots and 10 dashes and for all of the messages.

What I claim as my invention is—

1. The combination of a make and break device having contacts to transmit dots, means whereby said device is also operative 15 to transmit dashes, whereby the dots and dashes are all transmitted through the same contacts, a constantly operating motor, power transmitting means to transmit power from said motor to said device, and a key

20 to manually control said power transmitting means and whereby to start and stop the operation of the device at will and without stopping the operation of said motor, said power transmitting means comprising

25 two gear wheels arranged close together with a friction drive connection from one to the other, a pinion for driving one gear wheel, and a pinion driven by the other wheel, said last mentioned pinion being held

30 normally against rotation by the normal position of said key, whereby one gear wheel rotates continuously while the other one rotates intermittently under control of said key.

35 2. A structure as specified in claim 1, said power transmitting means comprising a normally closed friction clutch one member of which is held normally against rotation by the normal position of said key.

40 3. A structure as specified in claim 1, comprising a ratchet dog for normally preventing operation of said device, and means on said key to disengage said ratchet dog to permit operation of said device.

45 4. A structure as specified in claim 1, said make and break device comprising a stationary contact and a vibratory lever for engaging said contact, rotary means for engaging and vibrating said lever and a spring 50 applied to said lever to ensure the necessary vibratory movement thereof.

55 5. A structure as specified in claim 1, said means for operating said device comprising a toothed wheel held normally against rotation by a ratchet dog and a vibratory lever engaging said toothed wheel.

60 6. A structure as specified in claim 1, said means for operating said device comprising a normally closed friction clutch one member of which is constantly rotating and the other member of which is held normally against rotation by said ratchet dog.

65 7. A structure as specified in claim 1 said power transmitting means comprising a friction clutch one member of which rotates

constantly and the other member of which is normally held against rotation by the normal position of said key.

8. In a telegraph sending instrument, the combination of a make and break device 70 having contacts adapted to be connected with a line circuit to transmit electrical impulses, thereby to transmit either dots or dashes at will, whereby the dots and dashes are all transmitted through the same contacts, a constantly operating motor, power transmitting means to enable said motor to operate said device, and key actuated means for manually controlling said power transmitting means to start and stop said device 75 at will, thereby to transmit any desired number of impulses, either dots or dashes, without stopping the operation of said motor, said make and break device comprising a stationary contact and a vibratory lever one end of which serves as a movable contact to engage and disengage said stationary contact, a toothed wheel to vibrate said lever, a spring controlling said lever, a ratchet dog to normally hold said wheel against rotation, and means actuated by said key to disengage said dog to start the operation of 80 said device.

9. In a telegraph sending instrument, the combination of a make and break device 85 having contacts adapted to be connected with a line circuit to transmit electrical impulses, thereby to transmit either dots or dashes at will, whereby the dots and dashes are all transmitted through the same contacts, a constantly operating motor, power transmitting means to enable said motor to operate said device, and key actuated means for manually controlling said power transmitting means to start and stop said device 90 at will, thereby to transmit any desired number of impulses, either dots or dashes, without stopping the operation of said motor, said make and break device comprising a stationary contact and a vibratory lever one end of which serves as a movable contact to engage and disengage said stationary contact, a toothed wheel to vibrate said lever, a spring controlling said lever, a ratchet dog to normally hold said wheel against rotation, and means actuated by said key to disengage said dog to start the operation of 95 said device.

10. In a telegraph sending instrument, the combination of a make and break device 100 having contacts adapted to be connected with a line circuit to transmit electrical impulses, thereby to transmit either dots or dashes at will, whereby the dots and dashes are all transmitted through the same contacts, a constantly operating motor, power transmitting means to enable said motor to operate said device, and key actuated means for manually controlling said power transmitting means to start and stop said device 105 at will, thereby to transmit any desired number of impulses, either dots or dashes, without stopping the operation of said motor, said key actuated means comprising two key levers arranged to swing in a horizontally disposed plane, one key for transmitting the dots and the other key for transmitting the dashes.

110 11. In a telegraph sending instrument, the combination of a make and break device 115 having contacts adapted to be connected with a line circuit to transmit electrical impulses, thereby to transmit either dots or dashes at will, whereby the dots and dashes are all transmitted through the same contacts, a constantly operating motor, power transmitting means to enable said motor to operate said device, and key actuated means for manually controlling said power transmitting means to start and stop said device 120 at will, thereby to transmit any desired number of impulses, either dots or dashes, without stopping the operation of said motor, said key actuated means comprising a pair of key levers arranged to swing in a 125

130

- horizontally disposed plane, a ratchet device between said key levers, for normally holding said make and break device open, and means on said key levers to control said ratchet device.
11. The combination of a make and break device to transmit dots, means whereby said device is also operative to transmit dashes, a constantly operating motor, power transmitting means to transmit power from said motor to said device, and a key to manually control said power transmitting means and whereby to start and stop the operation of the device at will and without stopping the operation of said motor, said power transmitting means comprising two gear wheels arranged close together with a friction drive connection from one to the other, a pinion for driving one gear wheel, and a pinion driven by the other wheel, said last mentioned pinion being held normally against rotation by the normal position of said key, whereby one gear wheel rotates continuously while the other one rotates intermittently under control of said key.
12. In a telegraph sending instrument, the combination of a make and break device adapted to be connected with a line circuit to transmit electrical impulses, thereby to transmit either dots or dashes at will, a constantly operating motor, power transmitting means to enable said motor to operate said device, and key actuated means for manually controlling said power transmitting means to start and stop said device at will, thereby to transmit any desired number of impulses, either dots or dashes, without stopping the operation of said motor, said make and break device comprising a stationary contact and a vibratory lever one end of which serves as a movable contact to engage and disengage said stationary contact, a toothed wheel to vibrate said lever, a spring controlling said lever, a ratchet

45
dog to normally hold said wheel against rotation, and means actuated by said key to disengage said dog to start the operation of said device.

13. In a telegraph sending instrument, the combination of a make and break device adapted to be connected with a line circuit to transmit electrical impulses, thereby to transmit either dots or dashes at will, a constantly operating motor, power transmitting means to enable said motor to operate 50 said device, and key actuated means for manually controlling said power transmitting means to start and stop said device at will, thereby to transmit any desired number of impulses, either dots or dashes, without stopping the operation of said motor, said key actuated means comprising two key levers arranged to swing in a horizontally disposed plane, one key for transmitting the dots and the other key for transmitting the dashes.

14. In a telegraph sending instrument, the combination of a make and break device adapted to be connected with a line circuit to transmit electrical impulses, thereby 70 to transmit either dots or dashes at will, a constantly operating motor, power transmitting means to enable said motor to operate said device, and key actuated means for manually controlling said power transmitting means to start and stop said device at will, thereby to transmit any desired 75 number of impulses, either dots or dashes, without stopping the operation of said motor, said key actuated means comprising a pair of key levers arranged to swing in a horizontally disposed plane, a ratchet device between said key levers, for normally holding said make and break device open, and means on said key levers to control said 80 ratchet device.

JOHN A. HULIT.
